UNITED STATES PATENT OFFICE

ROY F. CANNON, OF CLEVELAND, TEXAS, ASSIGNOR OF ONE-HALF TO S. E. RODGERS, OF LIBERTY COUNTY, TEXAS

DESIGN FOR A GAMING TABLE

Application filed March 20, 1931. Serial No. 39,170. Term of patent 14 years.

To all whom it may concern:

Be it known that I, ROY F. CANNON, a citizen of the United States, residing at Cleveland, in the county of Liberty, State of Texas, have invented a new, original, and ornamental Design for Gaming Tables, of which the following is a specification, reference being had to the accompanying drawings, showing the parts thereof.

I claim:

The ornamental design for a gaming table as shown.

ROY F. CANNON.
